DESIGN FOR A DRESS

Frances Prisco, New York, N. Y.

Application November 11, 1943, Serial No. 111,665

Term of patent 3½ years

To all whom it may concern:

Be it known that I, Frances Prisco, a citizen of the United States of America, residing in New York city, county of New York, and State of New York, have invented a new, original, and ornamental Design for a Dress, of which the following is a specification, reference being had to the accompanying drawing, forming part thereof, wherein

I claim:

The ornamental design for a dress, substantially as shown.

FRANCES PRISCO.
